HEAT RETAINING CURTAIN

Donald F. Walton, West Orange, N. J.

Application May 22, 1948, Serial No. 28,567

3 Claims. (Cl. 160—268)

1

The invention herein disclosed relates to a window curtain that is particularly adapted for reducing the transmission of heat through a window.

Heat travels through materials from the warmer to the cooler portion or side. The relative rapidity with which heat moves through materials is expressed as the coefficient of heat transfer. The quantity of heat transferred through material of a given coefficient of heat transfer depends upon the temperature gradient, i. e. the difference in temperature between the different sides or portions of the material.

In heated buildings it is the endeavor to maintain a specified temperature inside irrespective of the outside temperature. It is common practice to install radiators under windows. This practice results in a great waste of heat because window glass has a much higher coefficient of heat transfer than the ordinary wall and because as the heated air rises from the radiator there is a greater temperature gradient between the inside and outside of the window glass than there is elsewhere in the room.

An object of this invention is to provide a window curtain that reduces the heat transfer through the window. Another object of the invention is to provide a window curtain that reduces the temperature gradient of a window pane. A further object of the invention is to provide such a curtain that is readily and easily installed. Another object of the invention is to provide such a curtain that does not interfere with raising or lowering the shade or opening or closing the window.

The foregoing objects and certain advantages that will hereinafter appear are realized in the embodiment of the invention illustrated, by way of one practical embodiment thereof, in the accompanying drawing and described in detail below.

The drawing includes:

Fig. 1 which is an elevation of a window with the insulating curtain applied;

Fig. 2 which is a sectional elevation of the bottom rod taken on the line 2—2 of Fig. 1;

Fig. 3 which is a sectional elevation of the bottom rod taken on the line 3—3 of Fig. 1;

Fig. 4 which is a fragmentary, rear elevation of the rod taken on the line 4—4 of Fig. 3; and

Fig. 5 which is a fragmentary, sectional, side elevation taken on the line 5—5 of Fig. 1.

In Figure 1 of the drawing, there is shown in elevation, a window casement. This window casement includes stiles 1 and 2, an upper rail 3, a lower rail 4, and a window sill 5. Within the window casement and mounted between stiles 1 and 2, there is an ordinary window shade 6. This window shade is mounted on fixtures se-

cured to the inner side of the stiles, which fixtures are old and well known in the art.

The heat-retaining curtain of this invention is applied to the inside of the window casement. Primarily, the curtain includes a sheet of transparent material 7 that is of sufficient width to overlap the inside edges of the stiles 1 and 2. The sheet of transparent material is also of such length that it can extend from the rail 3 to the window sill 5. Desirably, the sheet 7 is a cellulose acetate sheet of approximately one thirty second of an inch in thickness.

One end of the sheet 7 is secured to a tension roller 8. This tension roller 8 is of a kind that is well known and commonly used in conjunction with window shades. The tension roller 8 is mounted in fixtures 9 and 10 that are secured to the rail 3. At the other end, the sheet 7 is secured to a hold-down rod 11.

The hold-down rod 11 is preferably longer than the width of the sheet 7. The particular rod 11, illustrated in the drawing, consists of a wooden rod 12 that is somewhat oval-shaped in cross section. A sheet metal casing 13, preferably chromium-plated, extends over the front of the rod and around the top and bottom of the rod. The sheet 7 extends down the back of the rod and is secured, as by staples, to the wood rod 12. Desirably, a fabric strip 14 is secured to the sheet 7 behind the rod 12 and serves to reinforce the edge of the sheet 7 and cover the staples by means of which the sheet is secured to the wooden rod 12. Handles 15 and 16 are secured to the rod and extend from the front surface thereof. These handles provide grips by which the curtain can be manipulated in a manner hereinafter described.

Adjacent each end of the rod, and near the side edges of the sheet 7, there are openings 17 and 18 provided through the rod. These openings are provided to receive releasable holding elements 19 and 20. At each opening, there is a metallic reinforcing collar or bushing such as the collar 21. The bushing 21 extends through the opening through the casing 13 and has outwardly extending flanges 21a and 21b which engage opposite sides of the casing 13 at the opening therethrough.

One of the holding elements, designated generally by the numeral 19, is illustrated in Figure 2. This holding element includes a shank 22 in the form of a wood screw that is screwed into the stile 1, adjacent the window sill. The shank 22 extends from a hexagonal head 23 which has a cylinder 24 formed integral therewith. A spring pressed plunger 25 is mounted in the cylinder 24 and carries a slidable latch 26 that engages the flange 21a of the bushing 21 to hold the rod against the stile. When the plunger 25 is pressed into the cylinder 24, the latch 26 is

retracted and the rod can be removed from the holding element. As shown in Fig. 2, the outer edge of the latch 26 is wedge shaped so that the rod can be pressed over the latch, and when the collar 21 passes the latch, the latch springs into place to hold the rod against the stile. When these holding elements are properly installed, the rod 11 is held against the stile and the bottom of the rod engages the window sill.

An opening 27 is also formed through the rod at the center thereof. A reinforcing collar 28 is provided about the edge of the opening through the sheet metal cover 13 of the rod, at the opening 27. This collar 28 is the same as the collar 21. Behind the opening 27, a grooved pulley 29 is rotatably mounted on the rod. For this purpose, there is provided a shaft 30 on which the pulley 29 is mounted. The shaft is secured to the rod by brackets 31 and 32. The pulley 29 is rotatably mounted on the shaft and is positioned centrally of the opening by bushings 33 and 34. The opening 27 and the pulley 29 are provided for a cord 35. The cord 35 is attached to the shade 6 which, when the curtain 7 is in place, is behind the curtain 7 and between the curtain and the window pane. By means of the cord 35, the window shade 6 may be raised and lowered without disturbing the curtain 7.

The curtain 7 is secured to the stiles 1 and 2 at spaced intervals by snap fasteners. One such snap fastener, designated generally by the numeral 36, is illustrated in Fig. 5. This snap fastener consists of a male element having a wood screw shank 22, that is screwed into the stile 1, and a spherical sector end 37 which cooperates with a female element 38 that is secured to the curtain 7, adjacent the side edge thereof. The element 38 is secured to the curtain 7 in the usual manner in which such snap fasteners are secured to fabrics or other sheet material. Fabric strips 39 and 40 extend along the side edges of the curtain 7. These strips cover the head end of the female elements 38. They are adhesively secured to the curtain 7 and serve to reinforce the edges thereof. By virtue of the cooperation between the tension roller 8, the hold-down rod 11, the holding elements 19 and 20, and the snap fasteners 36, the curtain is held against the window casement at all points. If one desires to open the window, it is only necessary to release the rod 11 from the elements 19 and 20, release the snap fasteners along the side edges of the curtain and the window is accessible. The handles 15 and 16 may be used to lift the curtain when it is not desired to release the curtain fully. When it is desired to remove the curtain, as during warm weather, the rod is released from the element 22, the snap fasteners disengaged and the curtain is rolled up in the manner of the ordinary window shade.

From the foregoing description of the embodiment of the invention illustrated in the drawing it will be apparent that by this invention there is provided a heat-retaining curtain for windows. The curtain is so constructed as to permit free manipulation of the shade without disturbing the curtain. The curtain is readily released from the window frame for removal or for opening or closing the window. It is to be noted that a cellulose acetate sheet such as that utilized in this curtain passes ultra-violet rays. Thus, with this curtain in place, and the window open, a child may receive the benefit of the ultra-

violet rays of the sun without being subjected to the outside atmosphere or drafts.

It will be obvious that various changes may be made by those skilled in the art in the details of the embodiment of the invention illustrated in the drawing and described above within the principle and scope of the invention as expressed in the appended claims.

I claim:

1. For a window including a window casement and having fastener elements secured in the window casement, a window curtain of the kind described comprising in combination a sheet of transparent material, a tension roller secured at one end of the sheet of transparent material, a holding rod secured at the opposite end of the sheet of transparent material and having openings therethrough adjacent each end thereof for receiving certain of said fastener elements secured in the window casement, snap fasteners secured at spaced intervals along the side edges of the transparent sheet for releasably securing the side edges to other of said fastener elements on the window casement, and a reinforcing fabric strip secured to the transparent sheet along the side edges thereof and covering said snap fastener.
2. For a window having a shade mounted between the stiles thereof and a cord fastened to the lower edge of the shade a window curtain of the kind described comprising in combination a sheet of transparent material, a tension roller secured at one end of the sheet of transparent material, releasable fastening elements secured at spaced intervals to and adjacent the side edges of the transparent sheet, a holding rod secured to the opposite end edge of the transparent sheet and having an opening for the cord attached to the shade adjacent the center thereof, and a pulley carried by the holding rod and rotatably mounted at the cord opening therethrough.
3. For a window having a shade mounted between the stiles thereof and a cord fastened to the lower edge of the shade a window curtain of the kind described comprising in combination a sheet of flexible, transparent material, a tension roller secured at one end of the transparent sheet, a holding rod secured at the other end of the transparent sheet and having an opening therethrough adjacent each end thereof and an opening therethrough substantially at the center thereof for the cord attached to the shade, a pulley carried by the holding rod and rotatably mounted at the cord opening through the rod, a plurality of snap fasteners secured to the transparent sheet at spaced intervals along each side edge thereof, and a reinforcing fabric strip secured to the transparent sheet along each side edge thereof.
